UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A MIRROR-FRAME.

SPECIFICATION forming part of Design No. 18,963, dated March 19, 1889.

Application filed February 16, 1889. Serial No. 300,172. Term of patent 7 years.

To all whom it may concern:

Be it known that I, HENRY BERRY, a citizen of the United States, residing at Shelton, in the county of Fairfield and State of Connecticut, have invented and produced a certain new and original Design for a Mirror-Frame, of which the following is a specification, reference being had to the accompanying drawing, which forms a part thereof, and which shows a plan view of a mirror-back shaped in accordance with my design.

The leading features of my design consist in the circular backing having the radial scalloped figures about the edge thereof and the curved and tapered handle attached to said backing.

A is the mirror-back, which is circular in outline, and which has extending around it, except at the point where the handle is joined thereto, the series of radial scalloped figures a. The handle is joined to the backing at the interval between the scallops last referred to by a small semicircular scalloped figure, b, whence two diagonally extended and fluted figures, c,

at the top of the handles extend downward to the enlarged portion d of the latter. From this enlarged portion the handle curves downward and outward, diminishing in size meanwhile, and then the extremity is curved upward and inward to a convolution, e. Upon the handle appear rows of beaded figures f, which extend sinuously across the handle at intervals from the enlarged portion to the point where the extremity is turned upward.

I claim—

The design for mirror-frames, as herein shown and described, the same comprising the circular backing having the radial scalloped figures around the edge thereof, and the curved and tapered handle convolved at its end extending outward from the backing, as set forth.

In testimony whereof I affix my signature in presence of two witnesses.

HENRY BERRY.
